CABINET FOR A HIGH SPEED PRINTER

Carmine J. Antonucci, 537 Sterling St., Uniondale, N.Y.,
and Michael Cridland, 457 Richfield Road, Wilton,
Conn.

Filed Nov. 16, 1961, Ser. No. 67,553

Term of patent 14 years

(Cl. D26—5)

FIGURE 1 is a front perspective view of a cabinet for a high speed printer showing our design;

FIGURE 2 is a side elevational view;

FIGURE 3 is a front elevational view;

FIGURE 4 is a top plan view; and

FIGURE 5 is a rear elevational view thereof.

We claim:

The ornamental design for a cabinet for a high speed printer, as shown.
